UNITED STATES PATENT OFFICE

HENRY H. PETERSON, OF EDMUND, WISCONSIN

VENDING MACHINE

Original application filed October 27, 1927, Serial No. 229,213. Divided and this application filed August 6, 1929, Serial No. 383,901.

This invention relates to new and useful improvements in vending machines primarily adapted for use in the vending of cigars, and is divided from my co-pending application Serial No. 229,213, filed by me under date of October 27, 1927.

The primary object of the present invention is the provision of certain new and useful improvements in a coin controlled actuating device and including an actuating rod for rotating a revoluble magazine located within the casing and in which the articles to be vended are arranged, together with a coin controlled latch for locking the actuating bar.

Another very important object of the invention is to provide an improved coin controlled locking mechanism consisting of but few parts, and which at the same time will be strong, durable, practical, efficient in operation, and otherwise well adapted for the purpose designed.

Other objects and advantages of the invention will become apparent during a study of the following description taken in connection with the accompanying drawings, wherein:

Figure 1 is a fragmentary top plan view of the vending machine, the top wall of the casing being removed to better illustrate the application of my invention thereto.

Figure 2 is a fragmentary vertical enlarged section taken substantially on line 2—2 of Figure 1.

Figure 3 is an enlarged fragmentary vertical sectional view taken substantially on line 3—3 of Figure 2.

Figure 4 is a perspective view of the coin trip lever.

With reference more in detail to the drawings, it will be seen that I have designated generally by the reference character 5 a casing of suitable design, and having a false bottom wall 6 and a top wall 7. Mounted for turning movement within the casing and suitably pivoted in spaced relation with respect to the false bottom wall 6 is a relatively large circular plate 8 formed adjacent its periphery with concentric circular rows of openings within which are rigidly

arranged the lower end of vertically extending tubes 9.

The plate 8 is properly spaced from the false bottom wall 6 in a manner not shown, and said bottom wall is provided adjacent the front wall of the casing with a suitable slot or opening 10 from which extends through the front wall of the casing 5 a suitable chute that is equipped at its outer end with an article receiving trough 11.

Arranged around the peripheral edge of the circular plate 8 are spaced vertically extending pins 12 which pins are equal in number to the number of the article receiving tubes 9 and the purpose of these pins will be hereinafter more fully set forth.

The subject matter of the foregoing description forms no essential part of the present invention, but has been described and shown here somewhat in detail in order to clearly illustrate the application of the present invention in a vending machine of this character. Such structure just recited has been more fully set forth in the above-identified application, and a more detailed description thereof is believed unnecessary for the purpose of illustrating the application of the present invention.

Arranged within the casing 5 at the back wall thereof is a sheet metal housing 13, from the top wall of which depends a coin chute 14, the top wall of said casing being formed with a coin slot 15 in registration therewith (see Figure 2). The opposite corner of the casing 5 is equipped with a suitable bracket 16 through which is slidable one end of a control bar 17, the opposite end of the control bar being slidable through the housing 13 as well as in an opening in the back wall of the casing 5. The outer end of this bar is provided with a thumb button 18. Disposed about the bar 18 between the bracket 17 and an abutment 20 carried by said bar 17 is an expansible coil spring 21, the purpose of which is to normally maintain the outer headed end of the bar in projected relation with respect to the back wall of the casing as clearly indicated in Figures 1 and 3.

Pivoted at its inner end as at 19 to the

bar 17 at a point substantially intermediate the ends of the bar and extending toward the opposite side wall of the casing is a finger 22. The outer end of the finger 22 is normally swung outwardly of the bar 17 through the medium of a suitable spring 23 anchored at one end as at 24 to the bar 17. Adjacent its outer end the finger 22 is provided with a shoulder 25, and the pins 12 are adapted to be selectively engaged by the shoulder 25 of the said finger 22 so that when the bar 17 is forcibly moved inwardly in the direction of the arrow in Figure 1, the plate 8 will be caused to turn upon a suitable pivot provided therefor. The degree of movement of the bar 17 is equivalent to the distance between adjacent article tubes 9 of the inner and outer rows of tubes for a purpose presently to be described.

Obviously when the plate 10 is turned in the manner just described, the tubes 9 are successively brought into registration with the slot 10 in the false bottom of the casing 5 and the articles within the tube will drop therethrough to pass to the trough 11 where they may be readily removed by the purchaser.

Arranged within the housing 13 of the casing 5 is a horizontal trip lever 26, and a plate 27 is rigidly secured to one side wall of the housing 13, and this plate 27 is provided with a laterally extending pivot pin 28, which pin in turn passes through an opening 29 formed in the shift lever 26 intermediate the ends of said lever, whereby the lever is pivotally mounted within said housing 13.

As shown to advantage in Figure 2, the lever 26 is normally maintained in a horizontal position and one end of the lever extends beneath the chute 14, and at this end the lever is formed on its top surface beneath said chute with a V-shaped channel 30. The opposite end of the lever 26 is formed with a weighted head 31 that normally rests within a notch 32 in the push bar 17 for locking the push bar against longitudinal movement. However, when a coin is deposited within the machine the same will strike against the channeled end of the trip lever beneath the chute 14, overcoming the weight of the head 31 for releasing the lever from the control bar 17, whereupon the latter may be pushed inwardly for causing the turning of the article carrying plate 8.

To prevent the dropping of the coin from the lever 26 before the bar 17 has been pushed inwardly, said bar is equipped at a point in front of the housing 13 with an inwardly extending horizontal arm 32, said arm 32 provided at opposite ends with laterally extending oppositely directed arms 33 and 34 respectively. The arm 33 is fixed as at 35 to the bar 17 at a point on the bar in front of the housing 13 as before stated,

while the laterally extending end extension 34 is normally arranged beneath the coin receiving end of the trip lever 26, allowing the said trip lever to swing only to such an extent as to cause the disengagement of the head 31 from the slot 32 of the push bar but at the same time prevent the dropping of the coin from the slotted end of the trip lever 26, the coin being partially supported in the groove 30 by the lower end portion of the coin chute 14.

As soon as the bar 17 is forced inwardly against the action of the springs 21 the arm 32 and its lateral finger 34 will be caused to move inwardly thereby entirely releasing the lever 26 so that the coin may drop from the lever.

As the control bar 17 is pushed inwardly against the action of the spring 21, the finger 22 will have its shouldered end selectively engaged with the pins 12 for successively bringing the article carrying tubes 9 in registry with the slots 10 for dispensing an article therefrom into the trough 11, and the movement of the control bar 17 inwardly against the action of the spring 21 being equal only to the distance between the pins 12 the plate 8 will be moved or turned only a sufficient distance to bring one of the article carrying tubes 9 into registry with the opening 10 and immediately upon release of the said control bar 17 the spring 21 will act against the bar for urging the same outwardly of the casing to assume its original position.

From the foregoing, it will be seen that I have provided a coin controlled actuating mechanism for vending machines, that is comparatively simple in construction, consisting of but relatively few parts, and that the same is positive and reliable in operation, efficient in use, and thoroughly capable for fulfilling the requirements of a device of this nature.

Even though I have herein shown and described the preferred embodiment of my invention, it is to be understood that the same is susceptible to changes fully comprehended by the spirit of the invention as herein described, and the scope of the appended claim.

Having thus described my invention, what I wish to claim as new is:

In combination with a vending machine wherein the latter comprises a vending device, including a spring pressed reciprocating control bar, and a coin receiving chute, of a lever pivoted intermediate its ends and having one end thereof extending transversely of said control bar, said one end of the lever being provided with a weighted head adapted to be received in a notch in a control bar for positively locking the latter against longitudinal movement, said lever at its opposite end provided with a longitudi-

nally extending coin receiving groove adapted for disposition below the lower end of the coin chute, an angular arm secured at one end to said control bar and extending at right angles therefrom, said arm having its opposite end disposed at right angles thereto for disposition beneath the grooved end of said lever for limiting the movement of said lever upon its pivot, whereby the grooved end 10 of said lever may cooperate with the lower end of the coin receiving chute for retaining the coin partially in the lower end of said chute when said weighted head is moved out of the notch in said control bar, said 15 last mentioned end of said arm being adapted to be moved out of engagement with the grooved end of said lever only when said control bar is moved against the tension of the spring.

20 In testimony whereof I affix my signature.
HENRY H. PETERSON.
